UNITED STATES PATENT OFFICE.

HENRY J. DOOLAN, OF WASHINGTON, DISTRICT OF COLUMBIA.

AUTOMATIC TRAIN-STOP.

1,311,761.

Specification of Letters Patent.

Patented July 29, 1919.

Application filed October 19, 1918. Serial No. 258,824.

To all whom it may concern:

Be it known that I, HENRY J. DOOLAN, a citizen of the United States, residing at Washington, in the District of Columbia, 5 have invented a new and useful Automatic Train-Stop, of which the following is a specification.

This invention is a device for automatically stopping railway trains, trolley cars 10 and the like.

It is well known that the block system, as such, has greatly reduced the danger of railway travel, but the success of such a system depends entirely upon the personal equation *i. e.*, the responsibility of each and every employee of the railroad and the character of his attention to his duties. The human equation is such however, that engineers and motormen will occasionally take great 15 chances and endanger the lives of passengers unnecessarily. Some of the worst wrecks in the history of railroading have been brought about by the disregard of signals set against a train or car, as the case 20 may be, and the engineer or motorman taking a chance that he could get through without accident. One of the objects of the present invention is to make it impossible for the driver of an engine or motor car 25 to ignore or disregard danger signals, and to pass the latter when they have been so set as to make it dangerous to proceed. A further object is to provide means for automatically setting the air brakes and sanding 30 the tracks if an attempt is made to pass a danger signal. A further object is to provide means for indicating whether or not an engineer or motorman has disregarded a danger signal or attempted to pass a block 35 set against him. A further object is to provide means for indicating whether or not the block signal has been properly operated, so that the responsibility for an accident 40 may be definitely fixed. A further object is to provide means whereby the stopping device remains effective no matter how many trains or separate cars may pass the 45 danger signal.

The invention will be hereinafter fully set 50 forth and particularly pointed out in the claims.

In the accompanying drawing:—

Figure 1 is a side view of a portion of a locomotive to which my invention is applied. Fig. 2 is a plan view. Figs. 3 and 55 4 are detail views illustrating the air and

sand valves respectively. Fig. 5 is a side view of the semaphore and trip device. Fig. 6 is a plan view thereof.

Referring to the drawing, 10 designates 60 a semaphore arm of usual type, the same being supported by an upright post 11, and actuated in any suitable or preferred manner for adjustment to the various signal positions. When said arm is set for danger it projects in a horizontal position over the railway track. The free end of the arm 10 is provided with a wing or trip section 12, hinged at 13, to the body of the semaphore arm, and free to swing horizontally 70 in either direction. The swinging movement of said wing 12 is limited, however, by arms 14 rigidly secured to the body of the semaphore arm 10, and extend laterally therefrom, being bowed at 15 to provide in- 75 wardly projecting abutments 16 which are engaged by the wing 12, when the latter swings from its normal position. The ends of the abutments 16 and the free end of the wing 12 are provided with perforations 80 through which is passed a soft wire 17 the ends of which are engaged by seals 18. The wing 12 is normally held in central position by the wire 17 and cannot be moved in either direction without breaking said wire. 85

Mounted on the engine cab is a valve casing 20 connected with the air brake system, by pipes 21, a rotary valve 22 being carried by said casing and interposed between and controlling the communication be- 90 tween said pipes. Said valve is provided at its ends with angular handles 23. Said valve is also provided with a crank arm 24, connected by a link 25, with a valve 26, working in a sand box 27. The valves 95 22 and 26 are normally closed when the handles 23 are in an upright position. The handles 23 are perforated for the passage of soft wires 28, the ends of which are passed through perforated fingers 29 secured 100 to the valve casing 20, suitable seals 30 being secured to the ends of said wires. By this arrangement the handles 23 cannot be rocked in either direction without breaking the wire.

In practice, the valves 22 and 26 are closed by moving the handles 23 into an upright position, and said handles are maintained in this position by means of the wires 28. The wing 12 of each semaphore is also se- 110 cured to central position by means of the wire 17. When the parts are in this posi-

tion, if the semaphore arm 10 is moved to danger position, *i. e.*, horizontally, the wing 12 will lie in the path of movement of one of the arms or handles 23. Thus, if the engineer should ignore the signal and attempt to pass the same, the impact of the handle 23 against the wing 12 would break both the wires 17 and 28, whereupon the wing 12 would swing against, and be stopped by one of the abutments 16, and the resistance thus encountered would cause the handle 23 to be moved to horizontal position, thus opening the air valve and at the same time discharging sand to the track. In this manner the train would be stopped and the air brake could not be released until the valve 22 is again closed. The presence of the broken wire 28 indicates the engineer's guilt and the presence of the broken wire 17 corroborates the same fact. The absence of the wire 17 would indicate negligence on the part of the signal operator. However, in any event, after the wire 17 is once broken, the wing 12 always remains in such position that it will intercept and operate the valve handles of as many successive trains as may pass.

Having thus explained the nature of my invention and described an operative manner of constructing and using the same, although without attempting to set forth all of the forms in which it may be made or all of the forms of its use, what is claimed is:—

1. In an automatic train stop, the combination with a movably mounted semaphore arm, a trip-section pivoted to one end of said semaphore arm and free to swing from side to side, and means connected to the sides of the semaphore arm for limiting the sidewise swinging movement of the trip-section in either direction, of a vehicle provided with a valve-operating member arranged to engage said trip-section.

2. In an automatic train stopping device, the combination with a semaphore arm having a main section and a trip section pivoted at its rear end to the forward end of the main section, and means secured to the sides of the main section for limiting the swinging movement of the trip section, of a vehicle provided with a valve operating member arranged to engage said swinging member.

3. In an automatic train stopping device, the combination with a semaphore arm comprising a main section and a pivoted trip

section, and arms secured to the sides of said semaphore arm and having inturned bowed end portions forming abutments to limit the swinging movement of said wing member, of a vehicle provided with a valve operating member arranged to engage said swinging member.

4. In an automatic train stopping device, the combination with a semaphore arm provided with a swinging wing member, stop arms for limiting the swinging movement of said wing member, and breakable means for normally locking said swinging member against movement, of a vehicle provided with a valve operating arm arranged to engage said wing member.

5. In an automatic train stopping device, the combination with a semaphore arm provided with a swinging wing member, stop arms for limiting the swinging movement of said wing member, a soft wire connecting said wing member and said stop arms to lock said wing member against movement, and means for sealing said wire, of a vehicle provided with a valve operating arm arranged to engage said wing member.

6. In a train stopping device, a semaphore arm, a trip section pivoted to said arm, rupturable means for normally holding the trip section in alignment with said arm, and means for limiting pivotal movement of said trip section when the rupturable holding means has been destroyed.

7. In an automatic train stopping device, the combination with a semaphore arm comprising a main section and a pivoted trip section, and means connected with the main section for limiting pivotal movement of said section, of a vehicle provided with a valve operating member and rupturable means for normally maintaining said valve operating member in position to engage the trip section.

8. In a train stopping device, a fixed member, an oscillatory member supported thereby, a wire for normally holding the oscillatory member in a predetermined position with respect to the fixed member, said wire being rupturable by impact with a resisting body, and train stopping means co-operating with said oscillatory member.

In testimony whereof I have hereunto set my hand.

HENRY J. DOOLAN.
